STEPLADDER

Leroy Whitwood, Lakeland, Fla.

Application May 3, 1932. Serial No. 608,966

1 Claim. (Cl. 228—29)

This invention relates to the class of step-ladders and pertains particularly to a stepladder having adjustable legs.

The primary object of the present invention 5 is to provide a stepladder of the three-legged type in which an extensible foot forms a part of each leg which facilitates the level positioning of the stepladder on uneven or inclined ground or in other positions where it would not 10 be possible to use the ordinary type of step-ladder.

Another object of the invention is to provide a three-legged stepladder in which the third or back leg is pivotally attached to the ladder 15 platform and at its lower end is formed to provide two spaced portions between which a longitudinally extensible foot is adjustably held.

Other objects and advantages of the invention will become apparent as the description of 20 the same proceeds and the invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of 25 the invention as expressed in the appended claim.

In the drawing:—

Figure 1 is a view in side elevation of the ladder embodying the present invention;

Figure 2 is a front elevation of the same;

Figure 3 is a sectional view taken on the line 35 3—3 of Figure 1;

Figure 4 is a sectional view taken on the line 40 4—4 of Figure 2.

Referring now more particularly to the drawing wherein like numerals of reference indicate corresponding parts throughout the several views, the numerals 1 each indicate a front leg of the present stepladder between which legs the 45 steps 2 are secured. The upper ends of these legs 1 are connected to the top or platform 3 by means of the bracket plates 4 which are secured to the under side of the platform, as illustrated.

As shown, each of the legs 1 is slightly bowed 50 and the legs are so arranged that the lower ends flare outwardly or are divergently related. The steps 2 are braced by the brace rods 5 extending longitudinally therebeneath and passing at their ends through the legs 1, the ends of the rods 5 having securing nuts 6 thereon which bear 55 against the outer sides of the legs.

Pivottally connected to the brackets 4 is a third or back leg which is indicated as a whole by the numeral 7. This leg comprises the two 60 bars 8 which at their upper ends are maintained

in spaced substantially parallel position by rungs 9 and are pivotally attached to the bracket plates 4 as indicated at 10. The lower portions of the bars 8 of the back legs are curved inwardly and terminate in the relatively short 65 straight lower ends 11 which are in spaced parallel relation and between which slides longitudinally the extension foot 12. As shown, one of the rungs 9 is disposed in relatively close proximity to the upper ends of the straight portions 11 and when the extension foot 12 is in raised position the notch 13 in the upper end thereof receives this adjacent rung 9 so that the foot will be held against oscillation.

The extension foot 12 is in the form of an 75 elongated flat bar which fits snugly between the spaced lower ends of the rear leg bars 8, and has a longitudinal slot 14 therein through which passes the screw bolt 15 which is carried by and extended through the portions 11 of the back 80 leg bars 8. This screw bolt 15 is substantially T-shaped, having the flat cross head portion 16 which is secured to the adjacent bar by suitable screws and upon the other end of the bolt is threaded a thumb nut 17 which when tightened up against the portions 11 draw the same together to tightly frictionally grip the extension leg 12. The lower end of this leg 12 is pointed as indicated at 18, so that the leg will secure a firm hold in the ground or other surface upon 90 which it is placed.

The lower ends of the portions 11 of the back leg bars are connected and surrounded by a collar 19 which serves as a guide for the leg extension preventing its moving from its parallel 95 relation to the adjacent portions 11.

Each of the front legs 1 has extended therethrough a T-shaped threaded bolt 20 the head of which is counter-sunk in the inner face of the leg and secured by screws or other suitable 100 means in the same manner as the bolt 15.

Suitably positioned against the outer face of each leg 1 is a front extension leg 21 which is in the form of a flat bar having a longitudinally extending slot 22 therethrough which 105 starts at the lower end and terminates at substantially the transverse center of the extension. This slot receives the adjacent bolt 20 and threaded on the bolt 20 is a thumb screw 23 which is designed to be drawn up against the 110 adjacent extension to hold it in frictional engagement with the leg against which it is positioned.

Surrounding the lower portion of each leg 1 is a yoke or collar 24 through which the adjacent leg extension passes and by which it is guided and held in parallel relation to the leg to which it is attached.

Between the spaced upper portions of the bars 8 of the rear leg there are mounted upon a suit- 120

able cross rod 25, the spaced parallel arms 26 which are connected at one end by a shelf-board 27. The arms are of sufficient length from the supporting rods to their free ends to engage 5 under the top step 2 of the ladder when the ladder is opened for use.

A chain or other suitable coupling means 28 is connected between each of the front legs 1 and the bar 8 therebehind so that the separation 10 of the front and rear legs is limited.

Having thus described the invention, what is claimed is:—

A stepladder structure, comprising two front leg members arranged in spaced parallel relation throughout a portion of their lengths and having their ground engaging ends in divergent 15 relation, a top member connecting and having the upper ends of the legs attached thereto, step members connecting said legs, a rear leg comprising two elongated members each pivotally connected at one end to said top member and extending throughout a portion of their lengths

in spaced parallel relation and converging at their lower ends, the lower ends of said rear leg members being in spaced relation and further being straight and parallel through a portion of their length and to the lower ends thereof, cross brace bars connecting the members of said rear leg, a band surrounding the members of the rear leg at the lower ends thereof, an auxiliary leg comprising a relatively short straight member extending through said band and slidably positioned between the members of the rear legs, said auxiliary leg having a longitudinal slot therein, and further having a notch in its upper end, a bolt member passing through the members of the rear leg and through said slot, said auxiliary leg when in one position relative to the rear leg having the notch therein occupied by a cross bar connecting the rear leg members, and an auxiliary leg slidably adjustably connected with each of the first mentioned legs.

LEROY WHITWOOD.
